CLAIM

The ornamental design for a spa circulating jet unit, as shown and described.

DESCRIPTION

FIG. 1 is a front right top perspective view of a spa circulating jet unit according to the present invention.

FIG. 2 is a front view thereof.

FIG. 3 is a right side view thereof, the left side view being a mirror image thereof.

FIG. 4 is a top view thereof.

FIG. 5 is a bottom view thereof; and,

FIG. 6 is a rear view thereof.

The broken lines shown represent portions of a spa circulating jet unit and form no part of the claimed design.
